UNITED STATES PATENT OFFICE.

WALTER A. MYERS, OF BURLINGTON, VERMONT.

DISPLAY-CARD.

1,385,923.

Specification of Letters Patent. Patented July 26, 1921.

Application filed May 26, 1921. Serial No. 472,832.

To all whom it may concern:

Be it known that I, WALTER A. MYERS, a citizen of the United States, residing at Burlington, in the county of Chittenden and 5 State of Vermont, have invented a new and useful Display-Card, of which the following is a specification.

This invention relates to display cards, one of its objects being to provide a simple 10 and inexpensive device of this character designed primarily to be placed upon a can which serves to support the card and from which the card cannot be removed accidentally without the exertion of force sufficient to tear the card from the can.

A further object is to provide a card 20 which, when positioned on a can or the like, will be supported in an upright position so that matter printed thereon can be readily seen.

A still further object is to provide a display card which, prior to being set up for use, can be kept perfectly flat so that large 25 numbers of them can be shipped in compact bundles.

With the foregoing and other objects in view which will appear as the description proceeds, the invention resides in the combination and arrangement of parts and in 30 the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a plan view of a portion of the 40 display card and showing the relative position of the parts during the application of the card to a can or the like.

Fig. 2 is a rear elevation of the lower portion of a display card, the position of the can or other article engaged thereby being indicated by broken lines.

Fig. 3 is a side elevation of the lower portion of the display card, the can or other container being indicated by broken lines.

Fig. 4 is a section on line 4—4, Fig. 3.

Referring to the figures by characters of reference 1 designates a sheet of suitable stiff material, such as cardboard, and this strip is scored transversely, as indicated at 55 2, and 3 so as to provide the main portion 4 of the display card, a base 5 between the

scores 2 and 3, and a back flap 6. An opening 7 is cut into the display card or sheet so as to intersect the portion 5, the opposed walls of that part of the opening within the 60 portion 5 being arcuate and concentric with the center of the opening. The distance between these arcuate walls is slightly less than the diameter of the can or other article C to which the display card is to be applied. 65

The opening 7 has extensions 8 projecting into the portions 4 and 6 of the display card, the end walls of each of these extensions diverging outwardly as indicated at 9 while the longitudinal walls of the extensions are 70 preferably straight and parallel as shown at 10.

A tab 11 can be extended from the free 75 longitudinal edge of the portion 6, this tab being gummed.

In using the display card the same is placed with its printed face downward on the can or other article C the diameter of which is slightly greater than the distance between the arcuate walls of the opening 7. 80 The portion 5 of the display card is then pressed downwardly so that these arcuate walls will snap under the bead or annular extension C' at the top of the can or other container, leaving the straight parallel walls 85 10 of the extensions 8 above the container C. The portion 4 is then bent along the score 2 so as to be in an upstanding position and extending over the can or other object C while the flap 6 is also bent upwardly along 90 the score 3 so as to extend across the top of the can or other object C. As the end walls 9 diverge as described, it will be apparent that they will project outwardly past the bead or annular projection C', as indicated 95 in Fig. 4. The flap 6 is bent so as to engage the back of the portion 4 and is attached thereto by means of the gummed tab 11 as shown in Fig. 3. It is to be understood, however, that if preferred other means than 100 the tab 11 can be used for connecting the portions 4 and 6 together. With the parts thus assembled it will be noted that opposed portions of the base 5 will extend under the rib or annular extension C' and the straight 105 parallel walls 10 of the recesses 8 will rest on the top of the container or other article C. Thus the display card will be supported in an upright position where the matter thereon can be seen readily. The card will 110 be held securely in position and cannot be detached except by exerting force.

It is to be understood that this device can be formed of sheet metal, cardboard, or any other suitable material.

I claim:—

- 5 1. A display card comprising a strip of cardboard or the like foldable along transverse lines to form an upstanding body portion, an intermediate base portion and an upstanding flap, there being an opening intersecting the base portion and having opposed walls spaced apart a distance slightly less than the diameter of the article to be engaged by the card, there being extensions of the opening projecting into the body portion and the flap portion of the card and provided with diverging end walls.
- 10 2. A display card including a strip of material foldable along transverse lines to provide a body portion, an intermediate base portion, and an end or flap portion, means
- 15
- 20

for securing the flap portion to the body portion, there being an opening intersecting the base portion of the strip of material, said opening following the configuration of a supporting article to be engaged but being of slightly less diameter than the top end of said article, there being extensions projecting from the opening and into the body portion and the flap portion, said extensions having diverging end walls and providing longitudinal walls for engaging the top of the engaged supporting object.

In testimony that I claim the foregoing as my own, I have hereto affixed my signature in the presence of two witnesses.

WALTER A. MYERS.
